HANDBAG FASTENER

William C. Hiering and Frederick W. Goerdens,
Newark, N. J., assignors to The J. E. Mergott
Company, Newark, N. J., a corporation of Del-
aware

Application June 11, 1936, Serial No. 84,652

4 Claims. (Cl. 292—209)

This invention relates to hand bag frames, and more particularly to improvements in latches for retaining such frames closed.

Heretofore, latches for bag frames have included a hasp mounted on one of the frame members and a projection or depression on the other frame member cooperating with the hasp to hold the two bag frame members together. Such latches, while effective for the purpose intended, 10 obviously require operations upon both frame members, thus increasing the cost of making bag frames.

It is, therefore, an object of this invention to provide a latch for a hand bag, which requires 15 merely mounting on one frame member, and no operations on the other frame member.

A further object is the provision of a latch for hand bag frames which is extremely simple in construction, requiring only two parts.

20 These and other advantageous objects, which will later appear, are accomplished by the simple and practical construction and arrangement of parts hereinafter described and exhibited in the accompanying drawing, forming part hereof, and 25 in which:

Fig. 1 is a perspective view of a hand bag frame having our latch mounted thereon,

Fig. 2 is a transverse sectional view showing the 30 frame members brought together, with the latch in open position,

Fig. 3 is a similar view, showing the latch in closed position,

Fig. 4 is a plan view, partly in section, taken on line 4—4 of Fig. 2, and

35 Fig. 5 is an exploded, fragmentary view of our improved latch.

Referring to the drawing, in Fig. 1 is shown a hand bag frame comprising a pair of outwardly opening channelled frame members 1 and 2, each 40 being provided with upper flanges 3 and 4 respectively. Attached to flange 4 is a small metal plate 5, having projecting from each side thereof trunnions 6, journalled in bearings 7 formed in a sheet of resilient metal 10, which has adjacent 45 the bearings two spaced parallel slits to provide a flat spring 8, which preferably is bowed slightly. The bearings 7 are formed by bending the edges of the sheet 10 back upon themselves adjacent the spring 8.

50 The plate 5 is provided with tongue 9 which constantly bears against the spring 8, to retain the sheet 10 in a horizontal or in a vertical position, as shown in Figs. 2 and 3. The sheet 10 is preferably bent back upon itself to provide a 55 knob or handle, and is well adapted to receive surface ornamentation, or if desired, an orna-

mental bar of a cellulose compound or the like can be inserted in the bent over sheet 10.

In operation, to close the hand bag, the two frame members are brought together and the handle 10 forced down, against the action of the 5 spring 8 and tongue 9, to a vertical position over frame member 1. Inasmuch as an appreciable force is necessary to raise the handle 10 to the horizontal position, the frame members will remain latched together without fear of accidental 10 opening.

From the above description, it will be seen that we have provided a simple and effective latch for hand bags, which comprises few parts and requires no operations upon the frame members. It 15 is apparent that our latch is well adapted for use upon almost any kind of frame members.

The foregoing disclosure is to be regarded as descriptive and illustrative only, and not as restrictive or limitative of the invention, of which 20 obviously many embodiments may be constructed, including many modifications, without departing from the scope herein indicated and denoted in the appended claims.

Having thus described our invention, what we 25 claim as new and desire to secure by Letters Patent, is:

1. A latching device comprising a plate mounted on one of a pair of members to be latched, a flat sheet of resilient metal bent back upon itself to provide a handle, said sheet being cut adjacent one edge thereof to provide a flat spring, the edges of the sheet being bent to form bearings, trunnions on said plate journalled in the bearings, and a tongue on the plate constantly 35 engaging the flat spring.

2. A latching device comprising a plate attached to one of a pair of members to be latched, a handle hingedly connected to the plate, and spring means on said handle constantly engaging 40 the plate, said handle being adapted to be moved downwardly over the other member to hold the members together.

3. A latching device comprising a plate attached to one of a pair of members to be latched, 45 a flat sheet of resilient metal bent back upon itself to provide a handle and pivotally connected to the plate, and resilient means on said handle constantly engaging said plate.

4. A latching device comprising a plate attached to one of a pair of members to be latched, and a sheet of resilient metal having a portion to provide a flat spring constantly engaging said plate, said sheet of metal being pivotally connected to the plate.

WILLIAM C. HIERING.
FREDERICK W. GOERDES.
